STOVE FOR GALLEYS AND THE LIKE

Mahlon A. Klein, 741 S. Fremont Ave.,
Alhambra, Calif. 91803

Filed Sept. 18, 1967, Ser. No. 8,615

Term of patent 14 years

(Cl. D81—25)

FIGURE 1 is a left front perspective view of a stove for galleys and the like with the cover down, showing my new design; and

FIGURE 2 is a right front perspective view with the cover raised, showing in dotted outline a removable heating unit.

The back and bottom of the stove are conventionally plain.

The novel features of my design reside in the portions shown in solid outline.

I claim:

The ornamental design for a stove for galleys and the like, substantially as shown and described.
